UNITED STATES PATENT OFFICE.

LOUIS H. THULLEN, OF BROOKLYN, NEW YORK, ASSIGNOR TO HALL SWITCH & SIGNAL CO., A CORPORATION OF MAINE.

AUTOMATIC TRAIN OR CAR STOP SYSTEM.

1,293,579.

Specification of Letters Patent.

Patented Feb. 4, 1919.

Application filed January 21, 1916. Serial No. 73,284.

To all whom it may concern:

Be it known that I, LOUIS H. THULLEN, a citizen of the United States, and a resident of Brooklyn, county of Kings, State of New York, have invented certain new and useful Improvements in Automatic Train or Car Stop Systems, of which the following is a specification.

My invention relates to improvements in automatic train or car stop systems and more particularly to the provision of means for rendering ineffective the automatic stop devices depending upon the location of a train. Further and more specific objects, features and advantages will more clearly appear from the detailed description given below, taken in connection with the accompanying sheet of drawings, which forms a part of this specification.

In the drawings, Figure 1 illustrates a portion of the system embodying my improvements in one form, the figure being largely diagrammatic and certain parts being shown in section to more clearly illustrate the operation thereof. Fig. 2 is an end view of certain parts of the automatic stop apparatus shown in Fig. 1. Fig. 3 is a detail section of certain relay apparatus, having an electrically controlled valve, and Fig. 4 is a detail section of another of the electrically controlled valves.

Referring to the drawings, 1 represents the rails on which the cars or trains run. 2 represents a power conductor and 3 the trolley coöperating therewith. 4 represents one of a number of members fixed along the track and called ramps, that will be energized from the power conductor 2 through a circuit 5 when closed by a switch 6, operated by an electromagnet or relay 7. When it is desired that the train be stopped, suitable apparatus is arranged to deenergize the magnet 7 and open the switch 6. This can be accomplished by means of any suitable automatic signaling system. 8 represents a member pivoted upon a pin 9, carried by a casting 10, suitably secured to the car 11. The casting 10 carries a cylinder 12, in which operates a piston 13, carrying a piston rod 14, adapted to engage an upwardly extending arm 15 integral with the member 8. The piston rod 14 is provided with a contact

16 at its outer end, suitably insulated from the main portion of the piston rod, which contact is electrically connected with the trolley 3 and consequently with the power conductor 2 by means of a conductor 17, a suitable resistance 18 being included in the circuit.

Air is admitted to the left hand end of the cylinder 12 behind the piston 13 by means of a valve 19 controlled by an electromagnetic device 20, consisting of magnet windings 20^a around a fixed core 20^b acting when energized to attract an armature disk 20^c carrying a spindle 20^d to which the valve 19 is attached. (See Fig. 4). The armature 20^c is normally forced upward by springs 20^e so that the valve 19 is normally held in its upper position. The electromagnetic device 20 is adapted to be connected to the power conductor 2 by a conductor 21, when the trolley 3 is raised. For this purpose a switch 22 is included in the conductor 21 between the electromagnetic device 20 and trolley 3, which switch member is normally pressed against the trolley by means of a spring 23. When the trolley is raised, spring 23 causes switch 22 to be raised simultaneously and close the circuit of conductor 21 to the trolley 3 and power conductor 2. This energizes the magnet 20^a and causes the valve 19 to drop so as to close the exhaust port 24 and connect the cylinder 12 with the air in the train line through a port 25. This causes the piston 13 to be forced to the right, thereby forcing the arm 15 to the right, in the position shown in dotted lines at 26. When the magnet 20 is deenergized, valve 19 is raised by any suitable mechanism and the cylinder 12 to the left of the piston 13 permitted to be exhausted and the piston 13 is forced to the left by the arm 15, which is acted upon by a spring 27 for this purpose.

The member 8 is so positioned on the car that it is adapted to engage the ramps or members 4, as the car or train passes them. The member 8, with its pivot pin 9 is electrically connected with another electromagnetic device 30 by means of a conductor 31, which electromagnetic device 30 consists of a magnet winding 30^a around a fixed core 30^b and operating an armature disk 30^c carrying a spindle 30^d, the lower end of which acts

as a valve closing for closing a port 30^e when the magnet windings are energized. (See Fig. 3). Below the port 30^e is a chamber 32 in which is located a valve 32^a adapted to 5 open an exhaust port 32^b, to control the air on the train line and cause the application of the brakes to the car or train. The valve 32^a is normally pressed downwardly by a spring 32^c and the air pressure is normally 10 maintained the same on both sides of the valve 32^a through a small by-pass 32^d. When the magnet 30^a is deenergized, causing the spindle 30^d to open the port 30^e the pressure in the train line causes valve 32^a to be 15 raised and exhausted through the ports in chamber 32, below the piston, so as to cause the brakes to be applied. With the parts in the position shown in full lines, the current passes from the power conductor 2, to the 20 trolley 3, resistance 18, conductor 17, arm 15, pivot 9, conductor 31 to the electromagnetic device 30 and thence to ground through conductor 33, so that the electromagnetic device 30 is energized and the brakes prevented 25 from being set. As the train or car approaches one of the ramps 4, which may be at the entrance to a block in a signaling system, if the ramp 4 is deenergized by reason of switch 6 being open, then upon the member 8 engaging the ramp 4, it rocks the arm 15 away from the contact 16, so that the circuit of the electromagnetic device 30 is deenergized, causing the brakes to be applied. This engagement of the member 8 with the 30 ramp 4 causes the same to move to the position shown in dotted lines at 34, while the arm 15 moves to the position shown at 35, so that it is disconnected from the contact 16. If, however, the ramp 4 is energized 35 upon its being engaged by the member 8, by reason of the switch 6 being closed, indicating that it is safe to proceed and it is not desired that brakes be applied, then when the member 8 engages the ramp 4, the arm 15 will be disconnected from the contact 16 in 40 the same manner, but the electromagnetic device 30 will not be deenergized, because current will flow therethrough from the power conductor 2 through the conductor 5, switch 45 6, ramp 4, member 8, pivot 9, conductor 31 and electromagnetic device 30 to ground, so that the electric condition of the electromagnetic device is not altered by reason of the rocking of the member 8 upon its engagement with the ramp 4.

When the magnet 30^a is deenergized as above explained, and the armature 30^e is moved upwardly by the springs, the circuit to the magnet is again broken at 30^e , the 50 normal circuit from wire 31 through the magnet being from wire 31 through armature 30^e, a fixed contact 30^g, wire 30^h to point 30^k, windings 30^a and wire 33 to ground. Therefore the brakes will remain set until

the circuit (broken at 30^e) is in some way 65 again closed through the magnet 30^a. This is accomplished by the temporary closing of a shunt circuit 41 around the break at 30^e , this shunt circuit being closed by a switch member carried by a diaphragm 38^a in a 70 chamber 38. When air is admitted to the chamber by opening a hand valve 39, the diaphragm is raised, thereby closing the shunt circuit and causing the magnet 30^a to be again energized and the circuit again 75 closed at 30^e .

In many systems, as for example in systems wherein the trains or cars travel over a portion of the line in a subway and another portion of the line on the surface, it is 80 extremely important to make use of the automatic stop arrangement in the subway, whereas it is not desired to do so when running on the surface. When so running on the surface, it is desirable to move the member 8 to as great a distance from the track as possible, so that it will not be liable to hit objects which may be accidentally lying on the track or in its path, &c. This is accomplished by means of the electromagnetic device 20 and piston 13 and associated parts in the following manner. When the train or car proceeds from the subway to the surface, the trolley 3 is permitted to rise by reason of the power conductor 2 being at a greater distance 85 from the car than it is in the subway. When the trolley 3 rises in this manner, switch 22, acted upon by spring 23, closes the circuit of conductor 21 and thus energizes the magnet 20, its other terminal being connected to 90 ground through conductor 36. This causes air pressure to be exerted on the left hand end of the piston 13, so that piston rod 14 causes the arm 15 to move to the position shown in dotted lines at 26. This causes the 95 member 8 to be raised to the position shown in dotted lines at 37, so that it is out of the path of the ramps or members 4, and will not engage them when the car or train passes them and is also moved to a greater distance 100 from the track, so that the danger of its being hit by obstacles on the track is greatly decreased.

When the car enters the subway from the 115 surface line, the trolley 3 is depressed, thus opening switch 22 and deenergizing electromagnetic device 20. This causes the valve 19 to be raised permitting the left hand end of the cylinder 12 to be connected with the atmosphere through the port 24, whereupon 120 the spring 27, acting on the member 8 and arm 15, causes piston rod 14 and piston 13 to be pushed back to the left hand end of the cylinder, and the member 8 lowered, so that it is in position to engage the members or 125 ramps 4. The automatic stop mechanism is then again put into operative condition, whereas upon leaving the subway, the auto-

matic stop mechanism is automatically rendered ineffective to cause the application of the brakes. The parts carried by the casting 10 may be suitably insulated, by being connected to the car 11 through insulating support 40.

Having fully and clearly described these operations of the system embodying my invention in one form, sufficient to enable those skilled in the art to understand the same, what I claim as new and desire to secure by Letters Patent is:

1. An automatic train or car stop system having in combination with means for automatically causing the brakes to be applied, embracing members along the track and a member carried by the train or car adapted to engage said members along the track, means dependent upon the location of the car adapted to operate independently of the embracing members along the track and to render said automatic means ineffective to cause such application of the brakes, said last mentioned means consisting of automatic apparatus for removing said member carried by the train from its operative position where it is adapted to engage said track members.

2. An automatic train or car stop system having in combination with a power conductor, a trolley therefor, and automatic means for opening a circuit to cause the brakes to be applied independently of the power conductor, means adapted to operate said automatic means without opening said circuit whereby said automatic means is rendered ineffective to cause such application of the brakes depending upon a change in position of the trolley.

3. An automatic train or car stop system having in combination with a power conductor, a trolley therefor, and means for automatically causing the brakes to be applied, embracing members along the track and a member carried by the train or car adapted to engage said members along the track, means adapted to render said automatic means ineffective to cause such application of the brakes, said last mentioned means consisting of automatic apparatus for removing said member carried by the train from its operative position where it is adapted to engage said track members and electromagnetic means controlled by certain movements of the trolley for controlling the operation of said last mentioned automatic apparatus.

4. An automatic train or car stop system having in combination members along the track, means for electrically energizing and deenergizing said members, a member carried by the train or car adapted to engage said track members, means for automatically applying the brakes when said last member

engages said track members depending on the electrical condition of the latter; a power conductor; and means for operating said automatic means, without changing its electrical condition for preventing such application of the brakes depending upon the location of the car or train with relation to the power conductor.

5. An automatic train or car stop system having in combination members along the track, means for electrically energizing and deenergizing said members, a member carried by the train or car adapted to engage said track members, an electrical circuit the energization and deenergization of which controls the automatic application of the brakes, means whereby said last member controls the energization and deenergization of said circuit by engagement with said track members, a power conductor, a trolley therefor and means preventing said last member affecting the energization of said circuit responsive to a certain movement of said trolley to cause the operation of the last member.

6. An automatic train or car stop system having in combination members along the track, means for electrically energizing and deenergizing said members, a member carried by the train or car adapted to engage said track members, air brakes for said car or train, an electrically controlled valve for controlling the application of said brakes, means whereby said last member controls said electrically controlled valve when it engages said track members, a power conductor, a trolley therefor, a piston for moving said last member, electromagnetic means controlling the movement of said piston and a switch operated by movement of said trolley to affect the electrical condition of said electromagnetic means and cause said piston to move said last member to a position where it will not engage said track members.

7. An automatic train or car stop system having in combination members along the track, means for electrically energizing and deenergizing said members, a member carried by the train or car adapted to engage said track members, air brakes for said car or train, means whereby said last member causes the application of the brakes when it engages said track members and depending on the electrical condition thereof, a power conductor, a trolley therefor, a piston for moving said last member, electromagnetic means controlling the movement of said piston and a switch operated by movement of said trolley to affect the electrical condition of said electromagnetic means and cause said piston to move said last member to a position where it will not engage said track members.

8. An automatic train or car stop system

having in combination with brakes, members along the track, a member carried by the car or train and adapted to engage said track members, means for causing the application of the brakes upon said last member engaging said track members, a member adapted to automatically change its position depending on the location of the car or train,

and means automatically controlled by such change of position for moving said last member out of the path of said track members to make said last member ineffective to cause application of the brakes.

In testimony whereof, I have signed my name to this specification.

LOUIS H. THULLEN.
